MODULATION SYSTEM

Norman H. Young, Jr., Jackson Heights, N. Y., assignor to Federal Telephone and Radio Corporation, New York, N. Y., a corporation of Delaware

Application March 13, 1944, Serial No. 526,264

6 Claims. (Cl. 179—171.5)

1

The present invention relates to pulse generation, and more particularly to a system for generating pulses which are time-modulated in accordance with the characteristics of speech or other intelligence.

It is an object of the present invention to provide a system for generating time-modulated pulses.

It is a further object of the invention to provide a time-modulation system in which a base wave is caused to be raised or lowered with respect to the normal zero axis thereof.

It is a still further object of the invention to provide means for applying to a base wave displaced relative to its normal zero axis, a signal wave representing speech or other intelligence, so that the position of the base wave will be further laterally displaced toward or away from its normal zero axis in accordance with the characteristics of the modulating wave. It is an additional object of the invention to provide means for translating this speech-modulated laterally-displaced base wave into relatively narrow pulses the time displacement of which is a function of the modulating intelligence.

Other objects and advantages will be apparent from the following description of a preferred form of the invention and from the drawings, in which:

Fig. 1 is a schematic diagram of a time-modulated pulse generator embodying a preferred form of the present invention; and

Fig. 2 is a set of curves useful in explaining the operation of the invention.

In Fig. 1 is shown a high-frequency oscillator 4 producing a base wave of conventional sinusoidal character, such as indicated by the waveform 6. Oscillator 4 is connected to the primary of a coupling transformer 8. A source of speech current or other intelligence, represented by the amplifier 10, is connected to the primary of a second coupling transformer 14. The speech current from amplifier 10 may be as indicated by the waveform 12 as compared to base wave 6.

The secondary windings of coupling transformers 8 and 14 form parts of a series circuit which includes in addition a choke coil 16, an inductance coil L, and a source of polarizing voltage 18. This polarizing voltage may take the form of a substantially constant direct current of suitable value. A condenser 20 is shunted across the direct current input terminals as shown.

Coil L is provided with a core of readily saturable material, which for the purpose of the pres-

ent invention is designed to become saturated at a level considerably below the peak amplitude of the base wave 6. The B-H, or saturation curve for the core to be preferred is shown in Fig. 2.

Referring again to Fig. 1, three electron discharge devices consisting of triodes V₁, V₂ and V₃ are illustrated. V₁ is an amplifier tube having a grid-cathode circuit including the coil L. The grids of V₂ and V₃ are respectively connected to the anode and cathode terminals of V₁ through suitable coupling condensers. Each of triodes V₂ and V₃ is provided with a grid bias of such a value that only the positive portions of a received wave will be conducted. A further amplifier 22 is connected in the common output circuit of V₂ and V₃.

Considering now the operation of the system of Fig. 1, it will be observed that the coupling 20 transformers 8 and 14 are connected in series with the source of polarizing voltage 18. As a result, the base wave, the speech current, and the constant direct current will be mixed algebraically one with the other. However, to simplify the 25 description, each of these currents and its effect on the remainder of the system will be considered separately.

When current from the oscillator 4 is passed through the coil L, surges of voltage are produced 30 across it at about the instants the current passes through zero. This mode of operation is illustrated by the curves of Figs. 1 and 2, in which the wave 6 is shown applied to the saturation curve 24 of the core of coil L. The resulting projection illustrates the rate of change of flux in the readily saturable core of the coil. Since the saturation level is quickly reached, the flux density is, in effect, clipped at that point and remains constant at such value for a greater part of that particular alternation of the wave.

Since the voltage developed across coil L due to its reactance is a function of the rate of change of flux, and does not depend upon the instantaneous density of the flux, the output voltage 45 produced in the cathode-grid circuit of triode V₁ will take the form of a series of pulses 28, curve A, Fig. 2.

Pulses 28 have a width determined by the time required by the core of coil L to reach saturation 50 level. This saturation time determines in turn the shape of the curve 26 representing the rate of change of flux, as the shorter the saturation time the nearer the curve 26 will approach a rectangular pattern and the narrower will be 55 the pulses 28 produced during the time the flux

in the core is varying between its maximum limits.

As can be seen in Fig. 2, the pulses 28 are spaced apart equally in time due to their derivation from the sinusoidal wave 6. As a result of the alternating nature of the flux as shown by the rate of change curve 26, successive pulses 28 are of opposite polarity. The pulses 28 appear on the grid of tube V₁, and as a result of the inherent phase reversal in an electron discharge tube, output pulses 28a of similar nature but displaced 180° in phase will be obtained in the anode circuit of the tube. These pulses 28a are illustrated in curve B.

The grid of triode V₃ is connected to triode V₁ by a cathode-follower arrangement, so that the pulses appearing on the cathode of V₁, which are of the same polarity as pulses 28, are received on the grid of V₃. The grid of V₂ is connected to the anode of V₁ to receive the phase-reversed pulses 28a. However, each of the triodes V₂ and V₃ is biased to pass only positive pulses. After phase reversal through V₂ and V₃, the pulse outputs 28b and 28c of these tubes are shown in curves C and D respectively, the negative portions of pulses 28 and 28a being clipped off. Since the anodes of V₂ and V₃ are joined at point 29, the pulses appearing at that point are a combination of those shown in curves C and D, this combination being indicated by curve E. An additional amplifier 22 inverts the pulses shown by curve E so that they are of positive polarity as shown by curve F.

The above description has assumed a sinusoidal carrier wave 6 being passed through coil L. If now a polarizing voltage or potential of substantially constant value from source 18 be applied to base wave 6 as indicated by broken line 41 in Fig. 2, the wave will in effect be displaced laterally relative to its normal zero axis 34 to assume a new position 38 such as indicated by the points 42 displaced relative to points 40 on the normal zero axis 34. These new points 42 will be alternately to one side and the other of the corresponding points 40. Consequently when the wave 6 in its new position 38 is passed through coil L, the voltage pulses 28 produced as a result thereof will be time displaced along the time axis, and following the positioning of the points 42 will be grouped together in pairs. Curve F shows the grouping of the pulses after the D. C. bias has been added to the wave 6, and after the pulses of curve E have been inverted by their passage through amplifier 22. These new biased pulses are indicated at 28d.

If now speech current from source 10, such as shown by waveform 12, be superposed on the D. C. biased wave 38, wave 38 will be again displaced laterally with respect to the normal zero axis 34 within the limits of the audio range. The points 42 will accordingly be again longitudinally shifted along the axis 34 in "push-pull" manner according to the instantaneous value of the speech or other signal energy.

If the D. C. bias voltage is properly chosen, one limit of the audio range may be made to coincide with the position of the pulses 28b and 28c as indicated in curve E before their position is shifted by addition of the polarizing voltage. This preferable limit is indicated at 30 on curve F. The opposite limit of the audio swing is shown at 32 on the same curve. The output of amplifier 22 will thus be pulses which are time-modulated in respect to their relative spacing in accordance with the characteristics of the curve 12 repre-

senting the intelligence which it is desired to transmit.

While I have described above the principles of my invention in connection with specific apparatus, it is to be clearly understood that this description is made only by way of example and not as a limitation on my invention as set forth in the objects and the accompanying claims.

I claim:

1. In a pulse time-modulation system, a source of alternating current, an electron discharge device having an anode, a cathode and a grid, a saturable reactor element, a circuit connecting said source across the cathode and grid of said electron discharge device, said element being a part of said circuit and receiving current from said source to produce clipped voltage alternations, said grid and said cathode acting to conduct alternations of opposite polarity respectively to result in pulses of opposite polarity in the respective cathode and anode circuits of said device, a source of direct current of substantially constant value, means for introducing said direct current into said connecting circuit whereby the normal zero axis of said alternating current will in effect be displaced relative to the amplitude limits thereof, means for segregating the pulses of a given polarity appearing on the anode and cathode of said electron discharge device, and means for combining the segregated pulses of said given polarity to form a train of pulses.

2. A system according to claim 1, in which said connecting circuit includes a choke coil between said source of alternating current and said reactive element.

3. A system according to claim 1, in which said reactive element comprises a coil having a core of readily saturable material.

4. A system according to claim 1, in which said segregating means includes two additional electron discharge devices respectively connected to be controlled by energy from the anode and cathode circuits of said first-mentioned electron discharge device, and bias means for controlling the conductivity of each of said two additional electron discharge devices so as to pass only those received pulses which are of a given polarity.

5. In a pulse time-modulation system, a source of alternating current, an electron discharge device having an anode, a cathode and a grid, a saturable reactor element, a circuit connecting said source across the cathode and grid of said electron discharge device, said element being a part of said circuit and receiving current from said source to produce clipped voltage alternations, said grid and said cathode acting to conduct alternations of opposite polarity respectively to result in pulses of opposite polarity in the respective cathode and anode circuits of said device, a source of direct current of substantially constant value, means for introducing direct current from said source into said connecting circuit whereby the normal zero axis of said alternating current will in effect be displaced relative to the amplitude limits thereof, a source of speech current, means for superposing said speech current onto the alternating current in the circuit formed of said element, said cathode and said grid whereby the amplitude of the combined alternating and speech currents will vary with respect to the said effectively displaced zero axis in accordance with the modulating characteristics of said speech current, and means for mixing the pulses of a given polarity appearing on the anode and cathode of said electron discharge de-

vice so as to form a train of pulses grouped together in pairs, a variation in the amplitude of said speech current acting to cause a change in the time interval between pulses of each of said pairs.

6. In a pulse generating system, a source of alternating current, an electron discharge device having an anode, a cathode and a grid, a saturable reactor element, a circuit connecting said source across the cathode and grid of said electron discharge device, said element being a part of said circuit and receiving current from said source to produce clipped voltage alternations, said grid and said cathode acting to conduct alternations of opposite polarity respectively to result in pulses of opposite polarity in the respective anode and cathode circuits of said device, means for segregating the pulses of a given polarity appearing on the anode and cathode of said electron discharge device, the means for segregating including two additional electron discharge devices respectively connected to be controlled by

5 energy from the anode and cathode circuits of the first-mentioned electron discharge device, and bias means for controlling the conductivity of each of said two additional electron discharge devices so as to pass only those received pulses which are of a given polarity.
